UNITED STATES PATENT OFFICE.

JOHN W. GRAHAM, OF HINTON, WEST VIRGINIA.

TYPGRAPHICAL OR LINE-CASTING MACHINE.

1,226,204.

Specification of Letters Patent. Patented May 15, 1917.

Application filed May 20, 1915. Serial No. 29,347.

To all whom it may concern:

Be it known that I, JOHN W. GRAHAM, a citizen of the United States, residing at Hinton, in the county of Summers and State 5 of West Virginia, have invented certain new and useful Improvements in Typographical or Line-Casting Machines, of which the following is a specification.

My invention relates to typographical or 10 line casting machines such as linotypes of the original construction, wherein circulating matrices are released from a magazine in the order in which their characters are to appear in print and then assembled in line, 15 together with expanding spacers, the composed line brought in contact with the face of a mold, the mold filled with molten metal, to form a line of type or slug against the matrices, which produce the type characters thereon, and the matrices thereafter 20 returned to the magazine from which they were originally drawn.

More particularly it relates to that class 25 of machines, having a series of magazines in connection with means, whereby, any magazine of the series may be moved into operative position, and, wherein the magazines are individually removable, and exchangeable, and to that end are each mounted 30 in a rack, in such manner, that any desired magazine can be removed without interfering in any way with any other magazine of the series, and, wherein the series of magazines are so mounted that the machine 35 in its construction may be fitted with only one magazine, and any practical number of magazines may be added as desired, the construction and housing of the magazines, with their attendant racks, being such, 40 that no change whatever is necessary to add more magazines as desired, and I also provide means to steady and support the magazines in perfect alinement, when in and near the operative position and for this purpose 45 provide guides or rubbing blocks at each end of the racks, which support the magazines, and such rubbing blocks guide the rack in its line of travel, and I also provide means whereby that the magazines 50 when above the operative position, begin to move backward or away from the operator, and are then traveling on a line substantially transverse to the line of travel below the operative position, and I also construct the bent arms so that they are of less width in and above the bend, than below

it, to allow the racks to still rest on the one immediately beneath after they begin to rise above the bend in the arm. It is apparent to those skilled in mechanics, that the 60 racks in and below the operative position are resting, at right angles to the arm on which they are traveling, while those above the point of the bend are not lying at right angles to the arm at the point at which they 65 are engaged with the said arm, but are still lying at right angles with the arm as it is below the bend. It will be further apparent that if the arm above the bend was made as wide as below, the racks would have to 70 maintain a line of rest at right angles with the arm, and to do this the front end of the rack would have to rise up; this feature is overcome by our construction. I also provide a base which travels on the said 75 bent arms and supports the racks and magazines. It is fitted with nuts, which engage the screws to raise and lower the magazines, and I also provide hand and power means for raising and lowering the base, and its 80 supported racks and magazines.

In the drawings I have shown my invention applied to a linotype machine, but it will be obvious that it may be applied to other machines, and many changes and 85 variations made therein, without departing, from the spirit or principle of this invention.

Generally speaking I desire to be understood that I do not limit myself to any 90 specific form or embodiment, except, in so far as such limitations are specified in the claims.

Referring to the drawings, Figure 1 is a side view of a portion of a linotype machine, having my invention applied thereto. Fig. 2 is a rear view of the supporting arm A having attached, the shaft and bevel gears which operate the screws used in raising and lowering the magazines. Fig. 3 shows the 95 lever used in operating the power raising and lowering device. Fig. 4 shows the power raising and lowering device. Fig. 5 shows a section of the front end of a magazine, showing the verge in place, and also 100 shows the trip finger and part of the attached key rod. Fig. 6 shows a top view of the base B¹ showing the housings which guide its travel, on the arm A, and also shows the pieces B² with the holes to engage the screws to raise and lower the magazines. Fig. 7 shows a side view of the 110

base B¹. Fig. 8 shows a view of the base B¹ with a rack B attached, and the magazine M in place. Fig. 9 shows a side view of a section of a rack B, showing the dogs B² and the rollers B³, also showing the sheet iron lining B⁴, in the rack B. Fig. 10 shows a section of a magazine showing the strengthening bars M¹ extended out at their ends to act as stops, working in connection with the dog B² to hold the magazines in place, and shows the extended ends tapered at their rear corners so as to slip out freely when the magazine is to be removed.

Referring first to Fig. 1:

15 The magazines M are mounted in the racks B of which the lowermost rack B is made fast to the base B¹, and so set that when the base B¹ travels upward, or downward, the magazine M housed in the lowermost rack will come in exact operative position, and each additional rack is placed on and supported by the rack immediately below, and rests on the rollers B⁵ of the said lower rack, whose duty it is to support such rack above and allow the same to move backward, or forward, as the rack travels upward or downward. The racks B house and support one magazine, and such racks are independent and separate from each other, 30 and the series is so constructed as to be built up on the unit plan, that is the lower rack is fastened to the web B¹, by any desired means, and when the magazine is placed in the said rack the machine is then ready for 35 operation as a one-magazine machine. Other racks can be added as desired, as many as the stroke of the screws B⁸ can accommodate, in this instance being eight.

40 A¹ shows the arm which extends back from the main arm A, whose function it is to house and support, the distributing and channel entrance mechanism.

45 A² shows an arm or brace extending from a point near the top of the main arm A, down to the frame of the machine, this brace also acts as a guide for the front ends of the racks B, to keep them in direct line when in or near operative position.

50 C shows a shaft which extends across both forks of the main arm A, and is shown more clearly in Fig. 2.

55 C⁴ shows a bevel gear on the shaft C, which gear C⁴ meshes into the bevel gear C⁹, on the shaft C², which shaft has on its outermost end the hand wheel C³, for raising and lowering the magazine.

Referring to Fig. 2:

A is a back view of the forked arm which supports the magazines.

60 A⁵ shows the shoulder block made fast to the arm A, and drilled to receive the screws B⁸.

65 C¹ shows the bevel gears on the ends of the screws B⁸, which mesh into the bevel gears H, on the shaft C.

C⁷ shows a bevel gear on the shaft C near its center which intermeshes with the bevel gear C⁶ on the shaft C⁵, shown in Fig. 4.

The shaft C⁵ has on its other end the bevel friction wheel D¹.

C⁷ and C⁶ are used in connection with the power raising and lowering device, and will be explained in Fig. 4.

Referring to Fig. 3:

Fig. 3 shows the lever E which operates the power lowering and raising mechanism. It is forked in one end so as to lie in the slot D² in the sleeve D⁵, shown in Fig. 4, and is pivoted on the pin D³ so as to allow it to throw either one of the bevel friction wheels D⁴, into contact with the friction bevel wheel D¹. The friction bevel wheels D⁴ are made fast to the sleeve D⁵, which is fitted to the shaft D, by a loose key, which allows the sleeve D⁵ to slide endwise, on the shaft D a sufficient distance to engage either of its connected friction pulleys D⁴, with the friction pulley D¹, and thereby operate the raising and lowering mechanism in either direction as desired.

90 D⁶ is a pulley on the end of the shaft D which shaft and pulley is already on all machines of the class described.

Fig. 4 has been explained in Fig. 3.

95 Referring to Fig. 5, it shows the verge V housed in the slotted bar V¹, and pivoted between the pins V² and V³, and held down at its rear by the spring V⁴, thereby causing the front pawl V⁵ to hold the matrix in place.

100 V⁶ shows the trip finger engaged with the key rods V⁷ by a socket joint. V⁸ shows the pin on which the trip finger V⁶ is pivoted.

V⁹ shows the casting which is slotted to house the trip finger V⁶ and also the upper 105 end of the key rod V⁷.

Referring to Fig. 6, it shows the base B¹, looking down from the top, and showing its attached housings through which pass the forked arms A, and also shows B⁹, castings 110 bolted to the said base, and having threaded holes to engage the screws B⁸.

Fig. 7 is a side view of the base B¹ shown in Fig. 6.

Fig. 8 shows the rack B having in it the 115 magazine M, looking down from the top. B⁶ are the guide rollers shown side view in

Fig. 1. F shows the casting which houses the guide rollers B⁶, and is made fast to the rack B. B⁵ shows the rollers which support the rack immediately above the rack of which they are a part. B² shows the stop dog shown side view in Fig. 9. The

120 dotted lines in Fig. 8 show the strengthening bars on the underside of the magazine, two of which are made flush with the magazine at its sides, and two projecting outward and made beveled off so as to act as stops working in conjunction with the stop dogs B² to hold the magazines in place.

130

Figs. 9 and 10 have been explained in connection with Fig. 8.

In operating the machine any of the magazines of the series can be brought into operative position, by means of the hand wheel C³ or by power by moving the lever E to the right or left, thus engaging one or other of the friction wheels D⁴, with the friction wheel D¹ on the shaft C⁵. The bevel gear C⁶ on the shaft C⁵ operates the bevel gear C⁷, which is fast to the shaft C, whose attached gears H operate the screws B⁸ by means of the connected bevel gears C¹, thus raising or lowering the base B¹, and the magazines which the said base B¹ supports. The arm A guides the travel of the magazines M by means of the guide rollers B⁶, which guide the racks B in which the magazines M are housed.

As previously stated I have shown my invention by way of example and in a preferred way, and it is obvious that many variations and changes may be made therein, without departing from the spirit or principle of this invention.

Having described my invention, its construction and operation, what I claim and desire to secure by Letters Patent of the United States, is as follows:

1. In a typographical machine, in combination, a frame having a pair of spaced apart arms, a plurality of independent racks, removable magazines housed in said racks, and rollers on said racks adapted to guide their movement relative to said arms.

2. In a typographical machine, in combination, a frame having a pair of spaced apart arms, a plurality of independent racks, guide rollers on said racks coacting with said arms, and supporting rollers projecting above the plane of the rack on which they are mounted for supporting the rack next above out of contact with the magazine adapted to be carried thereby.

3. In a typographical machine, in combination, a frame having a pair of spaced apart arms, a plurality of independent racks, mounted between said arms adapted to carry removable magazines, rollers on each rack adapted to support the rack thereabove out of contact with the magazine carried thereby, means associated with the frame adapted to keep the racks in line against lateral movement, and means associated with the upper parts of the arms adapted to direct the racks rearwardly from the operator.

4. In a typographical machine, in combination, a frame having a pair of spaced apart arms, a plurality of independent racks adapted to contain removable magazines, guide rollers associated with each rack, a frame on which the racks are movable, means adapted to prevent lateral movement of said racks, and roller means associated with each rack adapted to support the rack

thereabove, that part of the frame with which the guide rollers coact comprising a pair of bent arms having a reduced width at the bend to permit the rollers to pass thereby.

5. In a typographical machine, in combination, a frame having a pair of spaced apart arms, a plurality of independent racks adapted to contain removable magazines, guide rollers associated with each rack, vertically disposed arms with which said guide rollers coact having their upper parts bent rearwardly to carry the racks away from the operator, a base traveling on said arms to support said racks, a threaded member associated with said base, screw means engaging said threaded member, and means for actuating said screw means to move the base relatively to said arms.

6. In a typographical machine, in combination, a frame having a pair of spaced apart arms, a plurality of independent racks adapted to contain removable magazines, guide rollers associated with each rack, vertically disposed arms with which said guide rollers coact having their upper parts bent rearwardly to carry the racks away from the operator, a base traveling on said arms to support said racks, a threaded member associated with said base, screw means engaging said threaded member, and means for actuating said screw means to move the base relatively to said arms; said means including a shaft having a gear connection with said screw means, and being so positioned as to actuate both sides of said base equally and simultaneously.

7. In a typographical machine the combination of a plurality of removable magazines, independent racks in which said magazines are housed, guide rollers on said racks, and supporting rollers affixed to each rack to support the rack immediately thereabove.

8. In a typographical machine the combination of a plurality of removable magazines, independent racks in which said magazines are housed, guide rollers on said racks, a supporting roller affixed to said rack to support the rack immediately thereabove, and castings at each side of said racks to hold them in alinement.

9. In a typographical machine the combination of a plurality of removable magazines, independent racks in which said magazines are housed, supporting rollers affixed to said racks to support the racks immediately above, castings at each side of said racks to hold them in alinement, and a pair of bent supporting arms to guide the magazines above operative position, backwardly from the operator, said arms having a reduced width above the point of the bend.

10. In a typographical machine the combination of a plurality of removable maga-

zines, independent racks in which said magazines are housed, guide rollers on said racks, rollers affixed to said racks to support the rack immediately above, means at 5 each side of said racks to hold them in alignment, and a pair of bent supporting arms to guide the magazines above the operative position, back out of the way of the operator, the said arms having a reduced width 10 above the point of the bend, and a base shiftable on said bent arms for supporting said racks.

11. In a typographical machine the combination of a plurality of removable magazines, independent racks in which said magazines are housed, guide rollers on said racks, a pair of bent supporting arms to 15 guide the magazines above the operative position and away from the operator, a base shiftable on the said bent arms for supporting the said racks, means to shift said base, and means whereby the racks and magazines above the operative position are 20

guided back and out of the way of the operator.

25

12. In a typographical machine the combination of a plurality of removable magazines, independent racks therefor, rollers affixed to each rack to support the rack immediately above, a pair of supporting arms 30 bent at their upper part, a base shiftable on said arms and supporting the said racks, means to shift said base, means whereby the racks and magazines above the operative position are guided rearwardly from the 35 operator, and means whereby the racks with their attendant magazines can be removed from the top without interfering with the working of the machine.

In testimony whereof I affix my signature 40 in presence of two witnesses.

JOHN W. GRAHAM.
